Application December 27, 1934, Serial No. 759,352

2 Claims. (Cl. 38—24)

This invention relates to an improvement in a pressing machine and more particularly to a shirt pressing machine for use in commercial laundries.

One object of the invention is to provide a more compact machine requiring less floor space than is commonly now used.

A further object of the invention is to produce a more inexpensive commercial press for heavy pressure requirements for use in commercial laundries.

A further object of the invention is to provide means to place a shirt on a form before pressing so that it assumes a form similar to that it takes on the body of a man.

A further object of the invention is to shape and lay a shirt or similar garment on a vertical buck whereby both sides of the garment can be attended by an operator remaining in one position.

A further object of the invention is to provide means to press both sides of a shirt while on the buck without removing the shirt from the buck.

Other objects of the invention will in part be obvious and will in part appear hereinafter.

In pressing machines commonly used in commercial plants, heavy pressure is required to obtain good results. The common practice is to have the buck over which the garment lies in a horizontal position using one side only and taking the garment off one side after ironing; also the heated head which is pivoted, is moved in a vertical direction in such a manner as to be brought down on the garment under heavy pressure by the operation of the control handles by an operator and when released separates from the buck a distance far enough to enable the operator to obtain easy access to the garment. The object of this improved design is to enable an operator to use both sides of the buck, and by the moving of the buck by the operator in contact with the head enables more direct pressure to be applied between the buck and the head without the use of the usual compound toggles, effecting a considerable saving in power.

The invention accordingly comprises the features of construction, combinations of elements, and arrangements of parts, which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Figure 1 is a cross-section of the pressing machine.

Figure 2 is a front elevation of the pressing machine.

Figure 3 is a perspective view of a modified buck member.

Figure 4 is a front view of the modified buck member.

Figure 5 is a top view of the modified buck member.

Figure 6 is a fragmentary cross-section of the buck taken on line 6—6 of Figure 1.

Figures 7 and 8 show the control valve in two positions.

In the illustrated embodiment of the invention 15 numeral 10 represents a frame supporting a heated head 11 steam being provided through inlet 72 and drainage provided through outlet 67, facing same is a pivoted padded buck 12. The buck 12 is provided with a shaft 13 which is ball- 20 pivoted at 14 resting in a support designated by numeral 15. This arrangement allows the buck to swing against and away from head 11 as well as allows the buck member 12 to be turned completely around on its pivot so that both surfaces 25 may be used for laying the garment for pressing or ironing purposes. This buck may be made of several different shapes and have more than two padded surfaces for pressing. In the accompanying drawings it merely shows two sides. The 30 buck may be conceivably box-shaped. As shown in Figure 1 the shape is for ironing shirts.

When the shirt is placed on buck 12 it is moved manually against heated head 11 where a cut-out 16 in the head is provided to receive projection 17.

For applying pressure to the garment in a pre-determined position of the buck the valve 18 is provided with an extended stem 19 which comes in contact with the projection 20 of the link 21 40 of the toggle 22. When the operator swings the buck 12 against the heated head 11 he causes the toggle 22 to become set in a fixed position as shown in dotted lines in Figure 1 and the projection 20 pushes on the extended stem 19 of the 45 valve 18 permitting the air or fluid under pressure to enter the cylinder 23, through air supply pipe 68 as shown in Figure 7. When the buck is released and the projection 20 no longer presses against lever 19, the same is brought back to 50 normal position by spring 64 which closes the intake in valve 18 and opens the outlet passage through 69, as shown in Figure 8.

The heated head 11 is slideable, it being mounted on the frame 10 through pins 24 and 25 cooper- 55

ating with which are springs 26 and 27. The pressure on the head is applied at its center at 28 through pin 29 so as to allow sufficient adjusting for equalizing the pressure throughout the surface of the buck.

The frame 10 is provided with a supporting bearing 30 carrying a shaft 31 on which cuff-pressing members 32 and 33 and neckband pressing member 34 are mounted, as shown in Figure 1 and by dotted line of buck 12 in Figure 2. An arm 35 is rigidly secured to shaft 31 and is actuated by pressure in the cylinder 36. To close the pressing levers 32, 33 and 34, air or fluid pressure is released through valve 37 by the operator into the cylinder 36 to move the piston in the usual manner to apply pressure of the heated heads on their respective bucks. This valve is controlled by rod 66 and is provided with a two way opening to admit and release fluid pressure. The companion buck member 43 and 44 for cuff pressing heads 32 and 33 are fixed on the arms 42 and 43. It should be noted that this arrangement allows the two cuffs and neckband of a shirt to be ironed at the same time as the body or bosom of a shirt because when buck member 12 is opened and turned around to iron the back of a shirt, if it is desired, the other side of the cuffs can be ironed during this operation without the use of any extra time. Opening of the buck member 12 from contact with head 11 is sufficient in distance to allow the turning of the buck on its pivot 15 so that the closest point at the lower portion of the buck member will always be slightly more than one-half the distance of the width of the buck member to clear the head member 11.

In operation, after the garment is placed on buck 12 the buck is brought into contact with heated head 11 by manual means. The links 21 and 44 of the toggle 22 are brought into a straight and rigid position and locked by pin 45 held against catch 46 on the arm of foot lever 47. To hold pedal 48 upwardly to be ready to receive pin 45 is a spring under tension designated by numeral 49. When the operator steps on pedal 48 the pin 45 is released by catch 46 so that the buck member swings open by its own weight coincidentally with the collapsing of the toggle 22. To start the opening of buck member 12 in the manner described there is a projection 50 on foot lever 47 bearing against link 44 to start the movement of link 44 to its open position. It will thus be seen that the buck is easily accessible for the placing of garments, particularly shirts, on a form similar to the form of the body of a man and the utility and novelty lies in the fact that the buck can be turned while the operator remains in one position.

Figure 2 is a front elevation and more clearly shows the position of the cuff and neckband pressing member in relation to the body of the shirt. Buck member 12 is shown in closed position and the surface shown in full view is designated by numeral 51 while the opposite surface of buck 12 facing head member 11 is designated by numeral 52. Thus it will be seen that both

sides of a garment can be ironed without the usual labor of taking the ironed portion off of a padded surface to use this same padded surface for the unironed portion of a garment. Dotted lines in Figure 2 indicate member 17 on buck surface 52.

Figure 4 shows a front view of a modified construction of a buck member wherein a buck member 55 instead of being rigid on an arm 56 is pivoted by a ball support shown by numeral 57 on the arm 56, the arm extending freely into the center of the buck member.

Figure 5 more clearly illustrates the structure of buck member 55 by showing a top perspective view of the modified buck member.

As shown in Figures 3 and 4 this modified buck 55 has the surface 58 offset downwardly to the surface 59 so that the collar may be kept out of the way while pressing the back of the shirt. The two surfaces are, however, of substantially the same length and the buck member is made long enough to take in the full length of each surface in order to prevent a mark being left by the cut-out.

The outward swinging of buck 12 is limited by lugs 60 and 61 and the inward swinging is limited by lugs 62 and 63. As shown in Figure 1 buck member 12 is provided with a hollow chamber to receive steam to heat the padding and absorb any excess moisture given off by the ironing of wet garments. When member 12 is in open position, the steam enters through inlet 71 and through opening in ball pivot 15 and when in closed position, inlet 71 is closed by the ball pivot and outlet valve 70 connected to the opening in the ball pivot connected to the chamber providing for outlet of any condensation.

As best shown in Figure 6 the shaft 13 is provided with a reinforcing collar 64 which is provided with pins 65-66 received in the forked end 67 of the link 21 to hold the buck 12 on shaft 13 in a vertical position to prevent the buck 12 from tipping to one side on the ball pivot 15.

Having thus described my invention, what I claim is:

1. A pressing machine comprising a frame, a vertical heatable head supported by said frame, a padded buck having a plurality of pressing faces, means for pivoting said buck on said frame so that it can swing between an inclined position and a vertical position in contact with said head and so that it can rotate about an axis perpendicular to the axis of swing, whereby any selected one of the faces may be brought into contact with the head.

2. A pressing machine comprising a frame, a heatable head supported by said frame, a padded buck having a plurality of pressing faces, means for pivoting said buck on said frame so that it can swing from an open position to a closed position in contact with said head and so that it can rotate about an axis perpendicular to the axis of swing whereby any selected one of the faces may be brought into contact with the head.
